UNITED STATES PATENT OFFICE.

HENRY J. P. WHIPPLE, OF NEW HAVEN, CONNECTICUT.

KNOB ATTACHMENT.

SPECIFICATION forming part of Letters Patent No. 508,195, dated November 7, 1893.

Application filed February 24, 1893. Serial No. 463,526. (No model.)

To all whom it may concern:

Be it known that I, HENRY J. P. WHIPPLE, of New Haven, in the county of New Haven and State of Connecticut, have invented a new Improvement in Door-Knobs; and I do hereby declare the following, when taken in connection with accompanying drawings and the letters of reference marked thereon, to be a full, clear, and exact description of the same, and which said drawings constitute part of this specification, and represent, in—

Figure 1, a view partly in side elevation and partly in vertical section of one form which a knob constructed in accordance with my invention may assume; Fig. 2, a view partly in vertical section of the right hand knob shown in the preceding figure; Fig. 3, a detached view in end elevation of the adjusting sleeve shown in Figs. 1 and 2; Fig. 4, a view in transverse section on the line $x-x$ of Fig. 1 showing the spring-pin employed to connect the left-hand knob with the spindle; Fig. 5, a detached view partly in vertical section of a knob showing another way of locking the adjusting sleeve; Fig. 6, a detached view in end elevation of the sleeve shown in Fig. 5; Fig. 7, a similar view of the locking sleeve shown in the same figure.

My invention relates to an improvement in door-knobs, the object being to produce a simple and durable article, adapted to be conveniently applied to doors, and accommodated to their thickness without the use of washers, and side screws, and presenting, when in place, a neat and finished appearance.

With these ends in view, my invention consists in the combination with the neck of a door-knob, of an adjusting sleeve mounted thereupon, and forming an extension thereof, and means for locking the sleeve in any desired adjustment.

My invention further consists in certain details of construction and combinations of parts as will be hereinafter described and pointed out in the claims.

As shown in Figs. 1 to 4 inclusive of the drawings, the right-hand knob A, to which the spindle B, is rigidly secured, has its neck A', reduced in diameter at its outer end, and furnished with an exterior screw-thread. Upon the said neck of the knob, so threaded, I locate an adjusting sleeve, which forms an

extension of the neck. The inner end C, of this sleeve is adapted in diameter to fit over the inner portion of the neck A' of the knob, while its outer end C', is made somewhat smaller, internally threaded, and thus adapted to take into the threaded and reduced outer end of the neck. The outer end C', of the sleeve is also adapted in size to enter the short socket D, formed to receive it in the center of the rose D', which is adapted in the ordinary manner to be secured to the door. It will be apparent that by turning the sleeve, its position on the neck may be changed, so as to virtually increase or decrease the length thereof, whereby the knob as a whole is accommodated to the thickness of the door, as will be set forth later on. The sleeve is locked in any desired position of adjustment upon the neck, by means of a spring-actuated dog E, located in a longitudinal recess e, formed to receive it in the inner end of the neck, and adapted in depth to permit the dog to be pushed down flush with the exterior surface of the same. This dog is attached at its inner end to a pin E', located in a socket e', formed in part in the neck and in part in the spindle B, and large enough to contain also a small spiral spring E² arranged to exert a constant effort to push the pin, and hence the dog, radially outward. To adapt the sleeve to be engaged by the dog, its outer end C, is constructed with one or more shallow longitudinal grooves c, as clearly shown by Fig. 3 of the drawings, which represents four of these grooves arranged quartering. Normally the dog is entered into one of these grooves, whereby the sleeve is prevented from rotation. When, therefore, it is desired to rotate the sleeve to change its adjustment, or for any other purpose, the exposed projecting end of the dog is engaged by the fingers, and the dog pressed inward against the force of the spring E², and disengaged from the sleeve, which may then be rotated.

The left-hand knob A² is removably connected with the spindle B through its neck A'. This connection may be made in any approved way, but I prefer to make it by means of a spring-pin F, having an enlarged head. This pin passes through a transverse hole a, formed in the neck to receive it, and through one of a series of holes b, formed in the adjacent end of the spindle. As herein

shown, the neck is constructed with a transverse groove a' , located in line with the hole a , and adapted to receive the head of the spring-pin, which is thus prevented from rotating. The object of this groove is to allow the head of the spring-pin to pass below the surface of the neck, and as stated to prevent the pin from rotating, and if the outer wall of the groove were cut away, the purpose of 5 it would be subserved just as well. When the knob, considered as a whole, is in its final adjustment, the head of the spring-pin will be located in the socket D^2 , formed in the rose D^3 , located on the opposite side of the door from the rose D' , which has already been referred to. By reason of this spring action, this pin, which is very convenient to use, is retained in place, while the knob is being handled and applied to the door.

10 In applying a knob in accordance with my invention, the knob A is first put in place, whereby the spindle B , is projected through the opposite side of the door. The knob A^2 is then applied to the projecting end of the 15 spindle, and attached thereto by means of the spring-pin F , which is passed through that one of the holes b , formed in the spindle which secures the closest adjustment of the parts. This may be described as the coarse 20 adjustment of the knob. There will still remain a little end-shake of the spindle, which is ordinarily taken up by washers, which are put in place before the knob A^2 , is secured to the spindle. Under my invention, however, I take up this end shake by turning my 25 adjustable sleeve until its outer end is nearly, or quite in engagement with the bottom of the socket D , in the rose D' . This adjustment will draw the cotter-pin into the corresponding socket D^2 , formed in the rose D^3 on the opposite side of the door. If it is desired to remove the knob from the door, that 30 may be done by disengaging the dog E , from the adjusting sleeve, and turning the same until the knob A' can be pushed inward sufficiently to cause the knob A^2 , to move outward far enough to expose the spring-pin F , which may then be removed, and the knob A^2 detached from the spindle, which may then 35 be withdrawn from the door with the knob A .

In Figs. 5 to 7 inclusive, I have shown another way of locking the adjusting sleeve. In this construction the said sleeve G , is constructed with an inwardly extending concentric flange G' , having four notches g , as seen by Fig. 6 of the drawings, arranged at equal 40 distances apart, and each adapted to receive a locking pin H , extending radially inward from a flange H' , formed at the outer end of a secondary sleeve H^2 , which corresponds in 45 its external diameter to the diameter of the enlarged inner end of the sleeve G . By providing its outer end with a flange H' , the said secondary sleeve, fits over the flange G' of the adjusting sleeve G , making a good joint between the two sleeves. A spiral spring I , encircling the neck J , of the knob J' , as shown

in Fig. 5, is arranged to exert a constant effort to engage the pin H with one of the slots g . When it is desired to unlock the sleeve G , the sleeve H^2 , is drawn back by the fingers against the tension of its spring J , whereby its pin H , is withdrawn from the slot g in the flange G' of the sleeve G , with which it was engaged, leaving the said sleeve free to be rotated.

It is apparent that I might make still further alterations in the construction of my improved knob, and I would therefore have it understood that I do not limit myself to the exact form herein shown and described, but hold myself at liberty to make such changes and alterations as fairly fall within the spirit and scope of my invention.

Having fully described my invention, what I claim as new, and desire to secure by Letters Patent, is—

1. The combination with the neck of a door-knob, the said neck being threaded, of a threaded adjusting sleeve mounted thereupon and extending beyond the end thereof, and means associated with and exposed upon the neck of the knob for locking the sleeve to the said neck in any desired position of extension therefrom, substantially as described.

2. The combination with the neck of a door-knob, the said neck being threaded, of an adjusting-sleeve mounted thereupon and extending beyond the end thereof, and internally threaded to take into the threads of the neck, and means associated with and exposed upon the neck of the knob for locking the said sleeve by its rear end to the neck to secure the sleeve in any desired position of extension therefrom, the said means being located in rear of the threaded portions of the neck and sleeve, substantially as described.

3. The combination with the neck of a door-knob, the said neck being threaded, of a threaded adjusting sleeve mounted thereupon, and extending beyond the end thereof, and constructed with locking notches located in its rear edge, and a spring-actuated locking device to enter the said notches and lock the sleeve against rotation, in any desired extension beyond the end of the neck, substantially as described.

4. The combination with the neck of a door-knob, the said neck being threaded, of an adjusting sleeve having its outer end threaded, mounted upon the said neck and extending beyond the end thereof, and constructed at its inner end with locking notches, and a spring-actuated locking-dog to enter the said notches, set into a transverse socket formed for it in the said neck to lock the sleeve in any desired position of extension beyond the said end of the neck, substantially as described.

5. The combination with the neck of a door-knob having a transverse hole and a depressed transverse shoulder, located at the extreme end of the said neck, of a rose adapted to receive the end of the said neck, a spindle con-

structed with a series of transverse holes, and adapted to be entered into the said knob, a spring-pin adapted to be passed through the hole in the neck, into one of the holes in the spindle, and having a head which engages with the said shoulder, which prevents it from turning, and which lets it down below the surface of the neck, and means for drawing the end of the neck of the knob into the

rose, so as to conceal the pin, substantially as so described.

In testimony whereof I have signed this specification in the presence of two subscribing witnesses.

HENRY J. P. WHIPPLE.
